[57] CLAIM

The ornamental design for a spoon or similar article,
substantially as shown.

DESCRIPTION

FIG. 1 is a top view of a spoon or similar article, showing
my new design;

FIG. 2 is a bottom view thereof;

FIG. 3 is a side view thereof;

FIG. 4 is a sectional view thereof looking in the direc-
tion of arrows 4—4 of FIG. 1, and drawn to an enlarged
scale; and

FIG. 5 is a sectional view thereof looking in the direc-
tion of arrows 5—5 of FIG. 1, and drawn to an enlarged
scale.
